UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING AND LOADING MACHINE.

Original application filed January 13, 1917, Serial No. 142,324. Divided and this application filed January 20, 1918, Serial No. 272,115. Renewed March 2, 1922. Serial No. 540,572.

To all whom it may concern:

Be it known that I, NILS D. LEVIN, a citizen of the United States, residing at Columbus, in the county of Franklin and State of Ohio, have invented certain new and useful Improvements in Mining and Loading Machines, of which the following is a specification, reference being had therein to the accompanying drawing.

10 This invention relates to certain new and useful improvements in mining and loading machines of the class adapted to break down previously undercut coal and load it into conveniently placed cars for removal from the mine.

The especial object of this invention is to provide, in a machine of the class described, an improved arrangement of conveying mechanism adapted to be positioned to receive the coal as it is broken down and remove it rearwardly of the machine, associated with breaking down devices which are adjustable relative to the said conveyers and to the material which is to be broken down.

25 The devices by which I attain this object are fully set forth in the following specification and illustrated in the accompanying drawings of which

Fig. 1 is a plan view of a machine embodying my invention, a portion of the machine being broken away to permit illustration on a larger scale than would otherwise be possible.

Fig. 2 is a side elevation of the machine.

35 Fig. 3 is a fragmentary side elevation showing the moving carriage upon which the drill or auger is mounted.

Fig. 4 is a vertical section on the line 4—4 of Fig. 1.

40 Fig. 5 is a vertical longitudinal section through a portion of the auger showing the hydraulic plungers mounted therein.

Fig. 6 is a transverse vertical section taken on the line 6—6 of Fig. 2.

45 Fig. 7 is a vertical section in the same plane as Fig. 6 showing a removable shaft section which is used at times in connection with the machine.

Fig. 8 is a vertical longitudinal section of 50 a part of the auger showing a modification of the coal breaking device.

Fig. 9 is a diagrammatic view of the face

of the coal showing the manner in which the auger is driven into the coal to break it down.

Referring in detail to the construction, A is the main frame of the machine; B is an endless conveyer mounted thereon; C is a carriage slidably mounted on the carriage frame A; D is an auger adjustably mounted 60 on the carriage C; E is a motor adapted to drive the auger and the conveyer B, and F is an auxiliary conveyer adapted to receive coal from the conveyer B and discharge it into the cars.

The main frame A consists of a horizontally extending pan-like structure 1 having a central longitudinally extending rib member 2 which divides the pan into two parallel troughs. In these troughs are disposed the moving parts of the conveyer B which latter consists of a chain 3 carrying suitably spaced vanes of flights 4. The rib part 2 serves as a guide for the conveyer chain. This chain preferably has its pivot joints alternately at 75 right angles to each other, as indicated in Fig. 1, so that the chain is universally flexible. This is necessary, because the rear part of the main frame A is inclined upward and rearward as shown in Fig. 2.

The main frame A has a plate-like extension 5 which underlies the upwardly inclined portion of the frame. A yoke 6 which is mounted on the plate or base 5 extends upward and over the main part of the frame 85 1 to which it is rigidly attached. On the upper end of the yoke is formed a bearing 7 for the vertical shaft 8, and the lower part of this shaft has a bearing 9 carried by the frame part 1. 10 is a sprocket wheel fast on the shaft 8 which drives the conveyer chain 3, the shaft being driven by the motor E. This motor is mounted upon a bracket 11 carried by the inclined part of the main frame A, the shaft 12 of said motor having a 90 bevel pinion 13 which meshes with the bevel gear 14 on the shaft 8. The endless conveyer at its front end passes over a sprocket wheel 15 which is suitably mounted on the frame A.

The carriage C consists of a base part 16 100 which is slidably mounted upon the rib 2 of the frame (see Fig. 4) and upstanding bearing arms or pedestals 17, 18. The motor frame 12 has a forward extending section

12^a. The rear end of the shaft section 12^a is supported by a bearing bracket 11^a and is connected by a disengageable clutch device 12^b to the motor shaft 12. The front end 5 of the shaft 12^a is disposed in the bearings of the pedestals 17, 18. Disposed between the pedestals 17 and 18 and mounted upon the shaft 12^a is a swinging yoke composed of two radius arms 19^a and 19^b. The rear 10 arm 19^a of this yoke is formed at its inner end with a segmental worm wheel 20. 21 is a worm which is mounted in a bearing bracket 22 secured to the pedestal 17 of the carriage. This worm meshes with the segmental worm wheel 20 and can be turned by 15 means of the crank 23 to cause the yoke to swing about its axis, it being understood that the shaft 12^a turns freely in the yoke.

The auger D is rotatably mounted in the 20 free ends of the yoke arms 19^a, 19^b, and is driven by a large spur gear 24 which is slidably keyed on the shaft 12^a and which meshes with a spur pinion 25 secured to the shaft of the auger D. The auger in its preferred form carries cutting tools 26, 26 at its front end. It will be seen that with the auger mounted in the manner shown and described, it is possible to drive it from the motor in any one of a variety of positions in 25 which it may be placed by swinging the yoke through something over one hundred and eighty degrees. The carriage C upon which the auger is mounted is, as it was stated, slidably mounted upon the main frame, and a screw 27 which is mounted in 30 its rear end in a bearing 28 and which at its forward end is threaded through the base of the carriage, serves to move the carriage backward and forward on the main frame, a hand crank 29 being provided to turn the 35 screw.

The auger D is provided with means for breaking the coal down after the auger has been driven into the coal. A preferred form 40 of the breaking means is shown in the drawing. A series of hydraulic plungers 30, 30 are mounted in cylindrical cavities 31, 31 formed in the auger, the cylinders and plungers being disposed transversely of the auger 45 and in one axial plane thereof. The cylindrical cavities 31, 31 communicate with each other through passages 32, 32, and the rear-most cavity of the auger is in communication with the passage 33 which leads to the rear 50 end of the auger shaft where it issues axially. 34 is a hand force pump which is mounted upon a bracket 35 of the carriage C. This pump has its suction passage in communication with a reservoir 36 which contains a 55 supply of water or other suitable liquid. The discharge pipe 37 of the pump is connected to a hose 38 which in turn is connected to the passage 33 of the auger, the hose being provided at its discharge end with a 60 nozzle 39 which extends through a suitable 65

stuffing box 40. 41 is a by-pass pipe leading from the discharge pipe 37 of the pump into the reservoir 36. The by-pass is controlled by a hand actuated control valve 42.

When the pump is actuated, the by-pass 41 being closed, the liquid is forced through the hose 38 and passages 32, 32 into the cylinders 31 and causes the plungers 30 to be forced outward. A spring 43 is mounted under the head of each of the plungers 30 and serves to 70 retract the plunger when the liquid pressure is withdrawn, which is done by opening the valve 42 in the by-pass 41 so that the liquid can flow freely back into the reservoir 36.

It will be seen that after the auger has been driven forward into the coal, as shown in Figs. 1 and 2, the hydraulic pressure can be applied to the plungers mounted in the auger to break down the underlying coal 85 upon the endless conveyer which extends into the bottom kerf, it being understood that said bottom kerf is previously cut by any of the well known undercutting devices. The coal thus broken down is carried rearward by the endless conveyer B, and in order 90 that it may be discharged into cars without manual labor, I provide the auxiliary conveyer F.

The conveyer F comprises a main frame 95 part 44 in the form of an elongated pan which is divided by a central longitudinal rib part 45 into two parallel troughs to receive the moving parts of the conveyer which, as shown, comprises a chain 46 and 100 flights 47. The conveyer frame 44 has its front and rear end parts horizontal with an intermediate inclined part. It is supported upon a truck 48, the rear end of the conveyer frame 44 being provided with a depending 105 pivot pin 49 which extends loosely through an aperture in the upper end of a bracket 50 on the truck. The frame 44 carries on its under side a wheel 51 which is designed to run upon an arcuate plate 52 on the truck 110 platform. Thus mounted on the truck, the frame can be swung through a considerable range about the pivot 49.

In operation the conveyer F has its receiving end disposed beneath the rear end of the 115 conveyer B, and preferably the conveyer F is driven from the motor E which drives the conveyer B. 53 is the driving sprocket wheel on the conveyer F, it being mounted on a short shaft 54 which is mounted in a 120 suitable bearing 55 carried by the pan 44 of the conveyer. (See Fig. 6). An idle sprocket wheel 56 for the conveyer chain 46 is mounted in a similar manner at the rear 125 end of the conveyer F. The upper face of the sprocket wheel 53 is formed with clutch teeth 57 which are adapted to be engaged by the teeth of a sliding clutch 58 which is slidably connected upon the lower end of the shaft 8 and which can be raised and lowered 130

by a hand lever 59. When the receiving end of the conveyer F has been moved under the discharge end of the conveyer B, the driving sprocket 53 of the former conveyer can be operatively connected to the shaft 8 of the conveyer B by simply lowering the clutch 58. In this way too the two conveyers are pivotally or flexibly connected to each other, and as the truck 48 is free to move on the track, it will be seen that the conveyer F will be automatically maintained in working relation with the main frame A of the machine when the latter is moved laterally along the face of the coal.

To effect the lateral movement of the machine along the face, I provide suitable power devices as follows:

On the base part 5 of the main frame A is mounted a stud shaft 60 upon which is rotatably mounted a spur gear 61. This gear has on its upper side clutch teeth 62 which are at all times in engagement with the teeth of a sliding clutch 63. 64 is a toothed clutch disc fast on the lower end of the shaft 54 of conveyer F, and by sliding the clutch 63 upward into engagement with the disc 64, the latter is connected to the gear 61. 65 is a suitably mounted hand lever designed to shift the clutch 63. 66 is a winding drum 30 arranged to turn about a vertical axis, and 67 is a large spur gear connected to said drum and mounted in mesh with the gear 61. One end of the cable 68 is secured to the winding drum 66 and thence extends to the left parallel to the face, passes over pulleys 69 and 70 which are anchored in any suitable manner by jacks or props 71, 72, and thence passes along the face of the coal to the machine, being made fast at 73 to the main frame A. It will be seen that when the clutch 63 is thrown to operative position, the winding drum 66 is turned causing the cable to be wound up and the machine to be drawn laterally along the face of the coal. Furthermore, the construction and arrangement of these devices is such that they are adapted to move the main frame laterally in parallelism so that it is maintained at the same angle to the coal face. 74 is a pulley 50 mounted on the base 5 at the left side of the machine, and is adapted to have the cable 68 passed over it and extended forward to a point adjacent the face of the coal and there made fast when it is desired to move the machine endwise into the bottom kerf.

It is at times desirable to drive the winding drum 66 when the conveyer F is not in operative position. To make this possible, I provide a short shaft section 75 which is shown in Fig. 7. This shaft is designed to be inserted between the movable clutch members 58 and 63 and is formed at its ends with teeth to engage the teeth of said clutch members. By inserting the shaft section 75, the gear 61 can be connected to the shaft 8

and driven from the motor E. In Fig. 8 I have shown a modified form of the breaking down devices carried by the auger. Referring to this modification, it will be observed that plungers 30' are mounted in sleeves 76 threaded into the body of the auger D' and springs 43' are interposed between the heads of the plungers and the sleeves, the relative arrangement of parts being much the same as in the hydraulic construction heretofore described and shown in Fig. 5. In the present case the plungers are thrust outward by means of a bar 77 which is slidably mounted in the auger D' and provided with cams 81 which slidably engage the heads of the plungers 30'. The cam bar 77 is moved endwise by means of a screw 78 which is threaded through a block 79 carried by the auger, has a swivel connection at one end with the cam bar 77 and is provided at its other end with a hand wheel 80. The cam bar 79 is held against rotation about its longitudinal axis by means of a screw 82 which engages longitudinal slot 83 in the cam bar. It will be seen that when the cam bar is forced inward by rotation of the cam wheel 80, the plungers 30' are forced radially outward to break down the coal, and when the cam bar is moved in the opposite direction the plungers are retracted by the springs 43'. 95

The operation of the machine will be readily understood from the foregoing description. Assuming, for the purpose of illustration, that the machine is to be used in a room and pillar mine, the procedure is as follows:

The coal having been undercut by any desired means, my breaking down and loading machine is set down adjacent the face of the coal, preferably at one of the ribs. In Fig. 1 I have shown the machine disposed in the corner of the room formed by the face and the right rib. The carriage C being fully retracted, the cable 68 is passed over the pulley 74 and carried forward along the side of the machine, as indicated by dotted lines in Fig. 1, and made fast at a point adjacent the face. The movable shaft section 75 having been placed in position between the clutches 58 and 63, the motor is now started so as to turn the winding drum 66 and draw the machine endwise toward the face of the coal. When the front end of the main frame A and the conveyer B have been projected fully into the bottom kerf of the coal, the motor is stopped, the shaft section 75 removed, and the conveyer F is run into operative position and connected by means of the clutch 58 with the shaft 8 of the conveyer B. 115

The yoke which carries the auger D is then swung over to the left by actuating the crank 23 until it approaches a horizontal position, as shown by dotted lines in Fig. 4. This brings the auger about into the position 125

corresponding to the circle *a* in Fig. 9. The motor is now started so as to rotate the auger *D*, and the carriage is gradually fed forward by turning the screw *27*.

5 The auger having been driven fully into the coal in this manner, the clutch *12^b* is disengaged so as to stop the auger with the hydraulic plungers *30* facing downward. The pump *34* is now actuated so as to force liquid 10 into the plunger chambers, and the plungers *30* are forced downward, the auger reacting upward against the overlying coal or rock. The downward pressure of the plungers causes a portion of the coal underlying the 15 auger to be broken down in the manner indicated in Fig. 9 of the drawing. The coal thus loosened falls upon the conveyer *B* which carries it to the rear and discharges it into the conveyer *F* which in turn discharges it into a mine car. The coal having 20 been forced down, the operator retracts the hydraulic plungers by opening the by-pass valve *42*.

25 The carriage *C* is now retracted by turning the screw *27* and the auger is then swung over to the right to a position preferably somewhat above that shown in full lines in Fig. 4 and indicated by the circle *b* in Fig. 9. The clutch *12^b* is now thrown into operative 30 position, the auger again fed forward, and the coal broken down and loaded into the car in the manner just described.

35 The carriage having again been retracted, the pulley blocks *69* and *70* are made fast at suitable points to the left of the machine, and the cable *68* is passed around the pulleys *69* and *70* and thence back to the machine to which it is made fast at *73*. The winding drum *66* is now started by throwing in the 40 clutch *63*, and the cable is thus wound up until the machine is drawn far enough to the left to make additional cuts with the auger. Preferably the machine will be moved far enough so that the auger, when swung 45 to an upright position, will occupy the position indicated by the circle *c* in Fig. 9. With the auger in this position, the carriage is again fed forward and the operation of drilling, breaking down and loading is repeated as before. In this manner the work 50 is continued until the machine has been moved clear across the face. During the progress of the machine along the face, the auxiliary conveyer *F* is gradually swung 55 about its pivotal support *49*, remaining constantly in operative relation with the main part of the machine and with the cars on the track.

60 While I have shown a preferred form of my invention, it should be understood that some of the parts can be modified without affecting the operation of other parts, and that some of the features are useful independently.

65 The subject matter of this application and

of the claims herein is characterized by the peculiar arrangement of the receiving and withdrawing devices, or conveyor, in relation to the devices for dislodging the coal and the devices for preparing for such dislodgment; and I do not herein claim the cutting apparatus or the dislodging devices by themselves considered; one form of mechanism for these purposes being presented in my application 588,471, filed October 22, 70 1910, renewed as 142,324, upon which was granted Patent No. 1,319,156, October 21, 75 1919, entirely irrespective of an automatically acting conveying mechanism related thereto in the manner herein set forth. 80

What I claim is—

1. In a mining and loading machine, the combination of a frame adapted to move laterally along the face of the coal, a conveyer mounted on the frame and adapted to enter a horizontal undercut in the coal, means on the frame for breaking down the coal upon the conveyer, an auxiliary conveyer having its receiving end pivotally connected on an upright axis to the discharge end of the first conveyer, and a movable support upon which the auxiliary conveyer is pivoted at its discharge end so as to swing laterally.

2. In a mining and loading machine, the combination of a frame, a conveyer mounted on said frame and adapted to project into a horizontal undercut in the coal, a cutter mounted on the frame above the undercut and adapted to be advanced into the coal, means for breaking the coal down upon the conveyer, a motor on the frame for driving the conveyer and the cutter, an auxiliary conveyer separably connected at its receiving end to the discharge end of the first conveyer, and disengagable driving connections between the two conveyers.

3. In a mining and loading machine, the combination of a frame adapted to move laterally along the face of the coal, a conveyer mounted on the frame and adapted to enter a horizontal undercut in the coal, means on the frame for breaking down the coal upon the conveyer, an auxiliary conveyer having its receiving end pivotally connected on an upright axis to the discharge end of the first conveyer, and a support for the discharge end of the auxiliary conveyer adapted to permit a combined swinging and endwise movement of said conveyer as the said frame is moved along the face of the coal.

4. In an apparatus for loading coal, the combination of a track extending at an angle to the face of the coal, a car on said track, 125 a frame movable along the face of the coal, breaking down mechanism supported on said frame, conveying and loading means adapted at its receiving end to be introduced under said face to receive the broken down coal 130

and extending thence rearward and upward to a point over said car and having its receiving end pivotally connected with said frame and having a pivotal support for its rear end, whereby said conveying and loading means is adjustable to different angles relative to the face of the coal and to said track, and cable means for moving said frame along the face of the coal.

5. In an apparatus for loading coal, the combination of a frame movable along the face of the coal, breaking down mechanism supported on said frame, conveying and loading means adapted at its receiving end 15 to be introduced under said face to receive the broken down coal and extending thence rearward and upward to a point over said car and having its receiving end pivotally connected with said frame and having a pivotal support for its rear end, whereby said conveying and loading means is adjustable to different angles relative to the face of the coal and to said track, and cable means for moving said frame along the 20 face of the coal.

6. In a mining and loading machine, the combination of a main frame adapted to rest upon and slide over the floor of the mine, a conveyer mounted on said frame 30 and adapted to project into a horizontal undercut in the coal, means to move said frame transversely in substantial parallelism, a cutter mounted on said frame and longitudinally movable relative thereto, and means within the bounding planes of the cutter and controllable by the operator to exert pressure transversely of said cutter to dislodge the coal above the conveyer.

7. In a mining and loading machine, the combination of a main frame, a conveyer mounted thereon adapted to enter a horizontal undercut in the coal, a cutter mounted on the main frame and movable longitudinally thereof adapted to form an incision in the coal, and means within the bounding planes of the cutter to exert pressure transversely thereof to dislodge the coal above the conveyer.

8. In a mining and loading machine, the combination of a main frame adapted to lateral movement transversely of a coal face, a conveyer rigidly mounted upon said frame and adapted to project into a horizontal undercut in the coal, a cutter movable longitudinally of the main frame to form an incision in the coal, and means within the bounding planes of the cutter to exert pressure transversely thereof to dislodge the coal upon the conveyer.

60 9. In a mining and loading machine, the combination with a main frame adapted to be positioned adjacent the coal face, a conveyer extending longitudinally thereof and adapted to enter an undercut in the 65 coal, a cutter longitudinally movable rela-

tive to the main frame to form an incision in the coal, and means within the bounding planes of the cutter adapted to exert pressure transversely thereof to dislodge the coal upon the conveyer.

10. In a mining and loading machine, the combination of a main frame, a conveyer mounted thereon adapted to enter a horizontal undercut in the coal, a cutter mounted on the main frame and movable longitudinally thereof adapted to form an incision in the coal, and means within the bounding planes of the cutter to exert pressure transversely thereof to dislodge the coal above the conveyer, and means within the control of the operator to control said dislodging means.

11. In a mining and loading machine, the combination of a main frame, a conveyer mounted thereon adapted to enter a horizontal undercut in the coal, a cutter mounted on the main frame and movable longitudinally thereof adapted to form an incision in the coal, hydrostatically actuated means within the bounding planes of the cutter to exert pressure transversely thereof to dislodge the coal above the conveyer, and means within the control of the operator to control said dislodging means.

12. In a mining and loading machine, the combination of a main frame adapted to rest upon and slide over the floor of a mine, a conveyer mounted on said frame and adapted to project into a horizontal undercut in the coal, means upon the main frame to co-act with abutments outside thereof to move said frame transversely in substantial parallelism, a cutter mounted on said main frame and longitudinally movable relative thereto, and means within the bounding planes of the cutter to exert pressure transversely thereof to dislodge the coal above the conveyer.

13. In a mining and loading machine, the combination with a conveyer adapted to project into a horizontal undercut in the coal, a cutter longitudinally movable relative to said conveyer to form an incision in the coal, and means within the bounding planes of the cutter to exert pressure transversely thereof to dislodge the coal above the conveyer.

14. In a mining and loading machine, the combination with a conveyer adapted to be positioned to receive and remove coal as it is broken down from the mine wall, a cutter movable relative to said conveyer adapted to form an incision in the coal, and means within the bounding planes of the cutter adapted to exert pressure transversely thereof to dislodge the coal upon the conveyer.

15. In a mining and loading machine, the combination with a conveyer adapted to be positioned to receive the coal as it is dis-

lodged from the mine wall, a cutter movable relative to the conveyer adapted to form an incision in the coal, and means within the bounding planes of the cutter and controllable by the operator to exert pressure transversely of the incision to dislodge coal onto the conveyer.

In testimony whereof, I affix my signature, in presence of two witnesses.

NILS D. LEVIN.

Certificate of Correction.

It is hereby certified that in Letters Patent No. 1,437,526, granted December 5, 1922, upon the application of Nils D. Levin, of Columbus, Ohio, for an improvement in "Mining and Loading Machines," an error appears requiring correction as follows: In the heading to the printed specification, line 5, the words "Original application filed January 13, 1917, Serial No. 142,324" should be *Original application filed October 22, 1910, Serial No. 588,471.*; and that the said Letters Patent should be read with this correction therein that the same may conform to the record of the case in the Patent Office.

Signed and sealed this 17th day of April, A. D., 1923.

[SEAL.]

KARL FENNING,
Acting Commissioner of Patents.
